UNITED STATES PATENT OFFICE

WILLIS O. PROUTY, OF HERMOSA BEACH, CALIFORNIA, ASSIGNOR, BY MESNE ASSIGNMENTS, TO METLOX CORPORATION, LTD., OF MANHATTAN BEACH, CALIFORNIA, A CORPORATION OF CALIFORNIA

DESIGN FOR A THERAPEUTIC LIGHT

Application filed July 24, 1931. Serial No. 40,678. Term of patent 14 years.

To all whom it may concern:

Be it known that I, WILLIS O. PROUTY, a citizen of the United States, and a resident of the city of Hermosa Beach, county of Los Angeles, and State of California, have invented a new, original, and ornamental Design for a Therapeutic Light, of which the following is a specification, reference being had to the accompanying drawings, forming part thereof, in which:

Figure 1 is a front elevational view of a therapeutic light embodying my invention; Fig. 2 is a side view thereof; and Fig. 3 is a top view thereof.

I claim:

The ornamental design for a therapeutic light substantially as shown.

WILLIS O. PROUTY.
